UNITED STATES PATENT OFFICE.

WILLIAM W. SMITH, OF EDGEWORTH, PENNSYLVANIA.

PUZZLE.

No. 826,902.

Specification of Letters Patent.

Patented July 24, 1906.

Application filed March 23 1906. Serial No. 307,690.

To all whom it may concern:

Be it known that I, WILLIAM W. SMITH, a citizen of the United States, residing at Edge-
worth, in the county of Allegheny and State
5 of Pennsylvania, have invented certain new
and useful Improvements in Puzzles, of which
the following is a specification.

This invention provides means to afford
amusement, as well as to acquire skill in the
10 manipulation of any article to be held in the
hand.

The invention appertains to a puzzle of the
type embodying a board or like support and
15 objects movable thereon by tilting the board
or support in different directions from the
horizontal.

An essential feature of the invention is to
afford diversion in devices of the type afore-
said, whereby one of the movable objects is
20 adapted to mount another one of the objects
and be carried thereby into an inclosure or
compartment, the object so carried being
designated as the "spider" or "rider," whereas
as the object ridden is designated as the "fly"
25 or "carrier." The carrier or fly in its nor-
mal condition by reason of its lateral extent
is prevented from entering the compartment
or inclosure; but when the spider or rider is
mounted thereon its lateral extent is reduced
30 by the folding of the wings or corresponding
parts to admit of the carrier or fly entering
the compartment or inclosure with its prey.

For a full description of the invention
and the merits thereof and also to acquire a
35 knowledge of the details of construction of the
means for effecting the result reference is to
be had to the following description and ac-
companying drawings.

While the invention may be adapted to
40 different forms and conditions by changes in
the structure and minor details without de-
parting from the spirit or essential features
thereof, still the preferred embodiment is
shown in the accompanying drawings, in
45 which—

Figure 1 is a perspective view of a puzzle
embodying the invention. Fig. 2 is a detail
perspective view of the butterfly or carrier,
the wings or laterally-extended movable
50 parts being omitted. Fig. 3 is a detail per-
spective view of the butterfly or carrier with
the spider or rider in position so as to effect a
folding of the wings of the carrier. Fig. 4 is
a central longitudinal section of the butter-

fly or carrier and the board or support, show- 55
ing the forward ends of the antennæ received
in the depression or opening of the board.
Fig. 5 is a transverse section of the butterfly
or carrier on the line *x x* of Fig. 4.

Corresponding and like parts are referred 60
to in the following description and indicated
in all the views of the drawings by the same
reference characters.

The board or support 1 may be of any size
and construction and is provided with a rim 65
2 to prevent displacement of the movable ob-
jects placed thereon. A portion of the board
or support is partitioned off to form an in-
closure or compartment 3, having an opening 4,
by means of which ingress and egress 70
are effected. For convenience the board or
support is illustrated as of rectangular form
and the inclosure or compartment 3 is ar-
ranged in one corner, the space inclosed by
the rim 2 being subdivided by partitions 5,
75 which are projected inwardly from adjacent
portions of the rim, the inner ends of the par-
titions being spaced apart a distance to form
the openings 4. Openings or depressions 6
are provided in the surface of the board or 80
support for the purpose presently to be ex-
plained.

The objects provided for coöperation with
the board or support 1 are of two types, the one
representing a butterfly or arthropod and 85
the other being spherical and designated as
the "spider." The sphere or ball 7 may be
of any material and is preferably designated
by the term "spider," although it may be
properly referred to under the general desig- 90
nation of "rider" because of its function—
namely, to mount the butterfly or like object
and be carried thereby into the inclosure or
compartment 3. The spider 7 may be of any
size and weight, the latter being important 95
because of its adaptation and coöperation
with the butterfly to effect contraction of the
lateral spread thereof.

The butterfly or analogous object may be
properly referred to as the "carrier," since its 100
purpose is to bring the rider safely into the in-
closure or compartment and without which
the carrier is prevented from entering said
inclosure or compartment because of its lat-
eral extent. The carrier comprises a body 8,
105 wings 9, and movable actuating part 10.
The body has a base portion 11 to obtain an
extended purchase upon the board or sup-

port, and its upper side is inclined, the rear ends being forked or bifurcated to provide a claw 12 to facilitate the entrance of the spider or rider and direct the same upon the back or 5 inclined top side of the carrier. The wings 9 are representative of movable parts which in their normal position prevent the butterfly or carrier from passing through the opening 4 and which folded by the spider admit of the 10 carrier passing through said opening. The movable actuating part 10 represents the antennae and the legs, the forward extremities of the antennae 13 being upturned, as shown at 14, to provide stops to retain the spider 7 15 in place. The legs 15 are rearwardly diverged and assist materially in placing the carrier laterally. The antennae and legs may be formed in any manner and preferably are of integral structure and are connected by a 20 cross-piece 16, which forms the pivotal connection between the movable actuating part and the body of the carrier. The legs 15 extend beneath the wings or movable parts and when thrown upward cause the wings or movable parts 9 to fold to reduce the lateral 25 spread of the device, whereby it is enabled to pass through the opening 4. The parts 13, 15, and 16 are portions of a single length of wire which is doubled upon itself and has the 30 folded end bent upon itself about as shown, the antennae and legs being arranged at an opposite inclination from a line corresponding with the cross-piece 16, whereby when the antennae are upwardly extended the legs 35 rest upon the surface of the board or support 1, but when said antennae are depressed by the spider 7 the legs are thrown upward and effect a folding of the wings or movable parts. The carrier in the preferred structure 40 being representative of a butterfly and the part 7 simulating the globular form of a spider are suggestive of the title by means of which the puzzle may be designated—that is, the "Spider and the fly." Obviously the 45 carrier may have any form so long as it embodies movable parts, and the spider may likewise be of any form whereby it is adapted to mount and ride upon the carrier and actuate one of the movable parts to effect a folding 50 of other parts to reduce its spread and enable it to enter the opening leading to an inclosure or compartment. The puzzle is solved by manipulating the board or support in a way to cause the rider to mount the carrier and actuate the part 10 so as to effect a folding of the wings 9, after which a tilting and manipulation of the board will cause the carrier to enter the inclosure or compartment, bearing the rider or spider captive. 55

60 In order to dislodge the rider from the carrier, the board or support is manipulated until the depressed portions of the antennae enter the openings or depressions 6, after which a sidewise tilting of the board will cause the 65 rider to clear the antennae, which will fly up-

ward at their outer ends by the superior weight of the legs 15 and the wings or movable parts 9.

Having thus described the invention, what is claimed as new is—

1. In a puzzle, a support adapted to be tilted from the horizontal, a carrier mounted upon the support and comprising movable members, and a rider adapted to be operated by manipulation of said board to cause it to 70 mount the carrier and effect movement of the said movable members.

2. In a puzzle, the combination of a board or like support, a carrier mounted upon the board and comprising movable members and 80 an actuating element, the rider likewise mounted upon the board and like the carrier adapted to be set in motion by tilting of the board to cause it to mount the carrier and operate the actuating element thereof to 85 effect movement of its movable members.

3. In a puzzle, the combination of a board or like support, a carrier comprising a movable actuator and pivoted members, and a rider for operating the actuator whereby the 90 pivoted members of the carrier are in turn operated.

4. In a puzzle, the combination of a board or like support, a carrier comprising pivoted members and an actuator, the latter embodying oppositely-inclined parts pivotally connected to the body of the carrier, and a rider mounted upon the board with the carrier, both adapted to be actuated by tilting of said board, whereby the rider is caused to 100 mount the carrier and operate the actuator to effect folding of said pivoted members.

5. In a puzzle, the combination of a board or like part, the carrier having a body and laterally-extended pivoted members, an 105 actuator pivoted between its ends to the body and having upwardly and forwardly extended portions and other parts extending upon opposite sides of the body, and a rider adapted to operate the actuator to 110 effect folding of the laterally-extended members of the carrier.

6. In combination, a board or like support adapted to be manipulated to effect operation of devices placed thereon, a carrier placed upon the board and comprising a body having its top side inclined, wings pivoted to the sides of the body, and a movable actuator embodying transversely-spaced upwardly and forwardly extended parts and members arranged upon opposite sides of the body and beneath said carrier and effecting depression of the forwardly-extended portion of the actuator, whereby the wings are folded, and a rider for operating the actuator to effect folding of the wings.

7. In combination, a carrier comprising a body, pivoted extensions and a movable actuator, the latter comprising a cross-piece and transversely-spaced forward and rear- 130

ward extensions, the latter being diverged and extending beneath the pivoted extensions of the carrier and along opposite sides of the body thereof, and a rider to mount the carrier and pass upon the forward extensions of the actuator and overbalance the same and effect a folding of the lateral extensions of said carrier.

8. In combination, a board or support having a depression in its surface, a carrier comprising pivoted members and a movable actuator, and a rider for operating the actuator and adapted to be dislodged from the part of the actuator supporting the rider when the same enters the depression in the surface.

9. A puzzle comprising a board having an inclosure, a carrier comprising pivoted members and a movable actuator, and a rider for operating the actuator to effect movement of the pivoted members of the carrier, whereby

the latter is enabled to carry the rider into the inclosure.

10. In a puzzle, the combination of a board having an inclosure provided with an opening, a carrier having pivoted members normally preventing the passage of the carrier through the opening leading to said inclosure, a movable actuator to effect movement of the pivoted members, and a rider to mount the carrier and operate the actuator to effect movement of the pivoted members of said carrier, whereby the latter is enabled to pass through the opening leading to the inclosure and carry the rider therewith.

In testimony whereof I affix my signature in presence of two witnesses.
